FORCE TRANSMITTING MEMBER

Carl F. Bachle, Detroit, Mich., assignor, by mesne assignments, to Continental Motors Corporation, Detroit, Mich., a corporation of Virginia

Application April 27, 1946, Serial No. 665,467

8 Claims. (Cl. 74—569)

1

This invention relates to a force transmitting member, such as a rocker arm in the valve actuating mechanism of an internal combustion engine.

In heavy-duty and high speed internal combustion engines, it is often necessary to provide very strong springs on the valves to insure proper closing. But strong valve-closing springs put an unusually heavy load on the valve actuating mechanism. In some types of engines, such as overhead valve types, the valve actuating mechanism includes a rocker arm. In order to reduce losses to a minimum, it is desirable to provide anti-friction devices wherever possible, as, for example, where the rocker arm engages the cam-shaft. In cases of this type, however, the problem is to provide an anti-friction device of sufficient strength to withstand the heavy loads involved.

It is the object of this invention to provide a force transmitting member, such as a rocker arm, in which the force in question is transmitted at one end to a member so constructed as to provide great strength while at the same time power losses are kept to a minimum by keeping friction to a minimum. This object is accomplished by means of a contact or bearing member in the form of a roller, rotatably mounted on a hub of softer material than the roller. The hub is mounted on a pin; hub and pin are keyed together against relative rotation, and the pin is secured against rotation relatively to the rocker arm. Sufficient clearance is provided between the roller and the hub to permit the formation of an oil film between them.

In the drawings:

Fig. 1 is a view in elevation of a rocker arm assembly embodying the features of this invention.

Fig. 2 is a partial section along the broken line 2—2 of Fig. 1.

Fig. 3 is a view in section along line 3—3 of Fig. 2.

Fig. 4 is an enlarged detail view of pin 8 shown before the ends are rolled over in the process of assembly; and

Fig. 5 is an enlarged detail view of the lock-pin used in the assembly.

In the embodiment shown, a force transmitting member such as a rocker arm 2 is adapted to pivot about the axis of any suitable stationary shaft cooperating with opening 4 in the rocker arm. At one end of rocker 2 there is provided a bifurcated member having fingers 6. Fingers 6 are provided with coaxial holes in which is mounted a

2

pin 8. A hub 10 is mounted on pin 8. A lock pin 12 is disposed between pin 8 and hub 10 to maintain these two parts in non-rotative relation to each other. Pin 8 and hub 10 together are held non-rotative relative to the rocker arm by rolling the ends of pin 8, as described below.

Pin 8 is grooved as shown at 14 of Fig. 4 to receive the lock pin 12. As shown in this embodiment, the axis of lock pin 12 falls substantially on the perimeter of contact between pin 8 and hub 10 so that lock pin 12 lies approximately half in groove 14 of pin 8 and half in a similar groove in hub 10. Also as shown in this embodiment, the ends 16 of lock pin 12 have been machined down so as to present a curved surface 18 having substantially the same radius of curvature as pin 8. If necessary to secure greater locking of pin 8 and hub 10 relatively to the rocker arm, it may be desirable to dispense with the machined ends 16 of lock pin 12, and extend the complete unbroken cylinder of lock pin 12 into cooperating grooves in the fingers 6 of the bifurcated arm. In assembling the completed rocker arm, the ends of pin 8 will be rolled over securely against the edges of the coaxial openings in fingers 6, in order to secure pin 8 against rotation relatively to the rocker arm. This rolling of the ends has been found sufficient to prevent turning of pin 8 on the fingers 6, without requiring any key between the pin 8 and the fingers.

A contact or bearing member, shown as a roller 20, is rotatably mounted on hub 10. Hub 10 and roller 20 will be made of materials so chosen that substantially all of the wear between the two members will take place on hub 10. Ordinarily roller 20 will be of hardened steel and hub 10 will be of a relatively soft bearing material such as bronze. Sufficient clearance will be provided between the inside diameter of roller 20 and the outer diameter of hub 10 so that when a contact force is applied in the direction of arrow 22, a small crescent-shaped annular space 24 is formed between roller 20 and hub 10 opposite the point of application of the force in question. Crescent-shaped space 24 will be large enough to permit the formation therein of an oil film which may be carried around into the region of contact between hub 10 and roller 20. Oil may be fed to the roller by means of passages 26 and 28 provided in rocker 2.

Operation

When the completed rocker arm is first assembled, hub 10 will be substantially circular in cross section, as will roller 20. However, as roller 20, of

relatively hard material, is rotated against the force of arrow 22 on relatively soft hub 10, the initial line of contact between the outside diameter of hub 10 and the inside diameter of roller 20 will soon wear down on hub 10 to a cylindrical area. Inasmuch as hub 10 is of a softer material, the contact area will assume substantially the radius of curvature of the inside diameter of relatively hard roller 20. In Fig. 3, the contact area is shown as being between points 30 and 32. The extent of this contact area will depend on the intensity of the force represented by arrow 22 and the softness of hub 10 relative to roller 20. Thus a bearing contact area will automatically form between hub 10 and roller 20. This contact area will be as much as, but no greater than, is necessary for the load in question, and will therefore be a minimum under the load conditions in existence and accordingly will offer a minimum of frictional resistance to rotation.

It will be seen from the foregoing that it is extremely important that hub 10 be held non-rotative in relation to rocker arm 2 because rotation of hub 10 would move the contact area out of the line of force represented by arrow 22. It is therefore imperative that hub 10 be securely locked against rotation.

I claim:

1. In a rocker arm, a bifurcated member having coaxial openings through the two fingers, a pin 30 non-rotatably mounted in the openings of the fingers, a soft-metal hub positively mounted against rotation on the pin, and a bearing member rotatably mounted on the hub.
2. A rocker arm having a bifurcated member, a pin non-rotatably mounted in the two fingers of the bifurcated member, a soft-metal hub positively mounted against rotation on the pin, and a hard-metal roller rotatably mounted on the hub.
3. In a rocker arm assembly, a bifurcated arm having coaxial openings through the fingers of the bifurcated member, a pin mounted in the openings of the fingers, a soft-metal hub mounted on the pin, a lock member between the pin and the hub, means to secure the pin against rotation relatively to the bifurcated arm, and a bearing member mounted on the hub, the bearing member being of harder material than the hub.
4. In a rocker assembly, a bifurcated member, a pin mounted in the fingers of the bifurcated member, a hub mounted on the pin, positive means engaging the pin and the hub to maintain them

non-rotative in relation to each other, means to secure the pin non-rotative in relation to the bifurcated member, and a bearing member of harder material than the hub rotatably mounted on the hub.

5. The invention set forth in claim 4, in which the inside diameter of the bearing member is sufficiently larger than the outside diameter of the hub to permit the formation of an oil film between the hub and the bearing member.

6. A valve actuating member having a bifurcated arm, a pin non-rotatably mounted in the bifurcated arm, a hub positively mounted against rotation on the pin, and a bearing member of harder material than the hub rotatably mounted on the hub, the bearing member having an internal diameter sufficiently larger than the external diameter of the hub to permit the formation of an oil film between the bearing member and the hub.

20 7. A valve actuating member having a bifurcated arm, a pin mounted in the arm, a hub mounted on the pin, a lock-pin between the pin and the hub, the ends of the first-named pin being securely rolled over against the sides of the arm to hold the pin non-rotatable in the arm, and a bearing member of harder material than the hub rotatably mounted on the hub.

8. A valve actuating member having a bifurcated arm, a pin mounted in the arm, a hub mounted on the pin, a lock-pin between the pin and the hub, the ends of the first-named pin being securely rolled over against the sides of the arm to hold the pin non-rotatable in the arm, and a roller of harder material than the hub rotatably mounted on the hub, the roller having an internal diameter sufficiently larger than the external diameter of the hub to permit the formation of an oil film between the roller and the hub.
